(57) **CLAIM**

The ornamental design for a display stand and holder combination for a portable electronic device, as shown and described.

DESCRIPTION

FIG. 1 is a front view of a display stand and holder combination for a portable electronic device showing my new design; FIG. 2 is a right side view thereof; FIG. 3 is a left side view thereof; FIG. 4 is a back view thereof; FIG. 5 is a top view thereof; FIG. 6 is a bottom view thereof; FIG. 7 is right front side perspective view showing the display stand and holder combination in an environment of use; and, FIG. 8 is right back side perspective view thereof.

The broken lines in FIG. 6 illustrate portions of the display stand and holder combination for a portable electronic device and the broken lines showing a mobile phone in FIGS. 7 and 8 illustrate environment; all broken lines form no part of the claimed design.

The invention provides a unique design of a display stand and holder combination for portable electronic device such as mobile phone. The display stand can be used to hold, display or rest a portable electronic device in different positions for different purposes including convenience, charging and or novel entertainment purpose.
